UNITED STATES PATENT OFFICE

GEORGE F. MURPHY, OF SCHENECTADY, NEW YORK, ASSIGNOR TO GENERAL ELECTRIC COMPANY, A CORPORATION OF NEW YORK

METHOD OF MAKING GRID STRUCTURES

Application filed July 1, 1930. Serial No. 465,163.

The present invention relates to electrical discharge apparatus, more particularly to thermionic devices containing an ionizable medium and provided with a source of electrons, a cooperating anode and an electrostatic control member (or grid). The present invention is directed more especially to the configuration and manufacture of a control member.

10 In devices of this character, the pressure of the ionizable medium, which ordinarily comprises mercury vapor or a fixed gas, and the impressed voltages are such that a discharge of arc-like character is produced between the electrodes, initiation of the discharge being controlled by the bias on the grid. After the arc is started, the grid loses control and can neither modulate, limit nor extinguish the arc. The starting of 15 the arc may be repeated indefinitely because while the discharge cannot be extinguished by the grid, it can be stopped by removing the anode voltage. Upon reapplying this voltage, the grid again determines whether 20 the arc will start, also the arc-starting position in the cycle, and by a continued repetition of this process the grid can control the average plate current over a period of 25 time. A practical method of obtaining interruption of the plate circuit is to employ 30 alternating current, although it will be understood that direct current may also be utilized in case proper circuit interrupting means are employed. Devices of this character have been described in an article entitled "Hot cathode thyratrons" in the General Electric Review, vol. 32, No. 2, April, 1929, pp. 213-223 inclusive and an article entitled "Hot cathode thyratrons" in the 35 General Electric Review, July, 1929, vol. 32, No. 7, pp. 393-4. Such devices find utility in circuits where large currents are to be controlled by the application of a very small amount of energy to the grid.

40 In tubes of this character, the grid or electrostatic control member surrounds the anode and is provided with perforations, the size and spacing of which determine some of the operating characteristics of the tube such as the grid control ratio, etc. In order to

obtain tubes which perform not only in a certain manner but also exhibit substantially duplicate characteristics when made in quantity, it may be necessary to provide the grid with extremely small openings which must 55 be of uniform size and shape. Nichrome, i. e. nickel-chromium alloy, is usually employed for grid material on account of its reluctance to emit secondary electrons and for other reasons, but the metal is tough to 60 work. It has been found practically impossible to punch a sheet of nichrome with holes much less than .025 inches diameter which are altogether too large for tubes of certain characteristics; the small punches invariably break under these conditions before 65 penetrating the entire thickness of the sheet. Drilling holes of this size or less would not of course be feasible from a quantity production standpoint. 70

An object of the present invention is to provide an improved grid and method of making the same, the grid being characterized by openings of minute and accurate dimension and the method of fabrication being adapted to metal which is unusually tough. This object is attained, in brief, by perforating sheet metal of greater than the required thickness with openings of larger than the required size, then reducing the 80 thickness of the metal by rolling or otherwise to the requisite thickness whereupon the metal in "cold flowing" will cause a reduction in the size of each opening to the required dimension, also a change in the 85 center-to-center spacing. Other objects and features will be apparent as the specification is perused in connection with the accompanying drawing. As an example of an additional feature, it has been found that the 90 rolling process offers a convenient method of obtaining openings of elongated shape, such as diamond, ellipse, etc., when the rolling is performed in a direction in which the elongation is desired. 95

In the drawing, Fig. 1 is an elevational view of a tube of the arc discharge type, partly broken away, and employing an electrostatic control member improved in accordance with my invention; Fig. 2 is a view 100

partly in elevation and partly in section of a perforating die; Fig. 3 is a plan view of the die; Fig. 4 is a section of perforated grid material before rolling, while Fig. 5 illustrates the material after rolling in a longitudinal direction and depicting an elongation of each opening in that direction; Fig. 6 shows the effect of rolling the material in transverse and longitudinal directions which 10 produces a marked reduction in the size of the opening; Fig. 7 is a modified shape of perforation in the sheet metal before rolling, and Fig. 8 shows the "elongating" effect of rolling the square-perforated sheet in one 15 direction to produce diamond-shaped openings. Fig. 9 illustrates the rolling operation.

In Fig. 1, numeral 1 designates an evacuated glass envelope provided at one end with a base 2 which has a plurality of contact 20 pins 3. A reentrant stem 4 extends within the envelope from the base end and serves to support a cathode 5 and grid member 6. The cathode may be of the indirectly heated 25 type with a filament 7 positioned in the cylinder 5; the latter may be coated on the exterior with an electron emitting material such as barium carbonate. One end of the filament is shown as connected to the closed top of cylinder 5 so that one of the rods 8 30 which support the latter from the press may also serve as a leading-in conductor for the filament. The other end of the filament is independently supported by a wire 9. The support rods 8 pass through and are connected to a metal plate 10 which protects the 35 stem from heat radiation and from positive ion bombardment. The wire 9 is extended through a large opening (not shown) in the plate 10, thereby being insulated from the 40 latter.

The grid or electrostatic control member, to which the present invention is directed, is constituted of mesh or perforated material and may take the form of a hollow cylinder 45 positioned within a drawn-down portion of the envelope. The grid is supported from the stem 4 by means of equi-distantly spaced rods 11, one end of which is bent and welded to a circular perforated plate 12 fitted with 50 in the grid. The other end of the rods is secured to a screw clamp 13 from which a lead is taken to one of the contact pins 3.

There is a plate-like anode 14, carbonized 55 to reduce secondary emission and to increase heat radiation, mounted within the grid by means of conductor 15 which is connected to an exterior contact 16 at the end of the envelope remote from the base. The tube is fabricated and assembled in the usual manner, the customary bakeout and heat treatments given, also a high degree of evacuation, after which a source of positive ions such as inert gas or a drop of mercury (not 60 shown) is admitted to the envelope. A device of this character when energized by

alternating current of suitable voltage operates as an electrostatically controlled arc discharge rectifier in which a small charge applied to the grid may control an average plate current of many amperes.

As stated hereinbefore, the grid control ratio, i. e. the ratio of the grid voltage necessary to restrain initiation of the arc discharge with respect to the plate voltage during the positive portion of the alternating current cycle is a function of the size and shape of the apertures in the grid, also the distance between apertures. It frequently happens that a control ratio is desired which necessitates a very small opening, less than .025 inches diameter and of accurate shape and size. When the grid is made of tough metal such as nichrome, it has been found, prior to my invention, that the procurement of holes less than .025 inches diameter in sheet metal .010 inches thick is practically impossible.

However, in accordance with my invention, I have discovered that if holes of a size larger than desired and sufficiently large to be readily punched are cut in sheet metal having a thickness correspondingly greater, the metal may be rolled to the proper thickness, and at the same time, the holes reduced to the proper size. It will be understood that the final thickness of the grid material is not so critical in determining the control ratio as the size of opening so that when the proper opening has been obtained by rolling, the latter operation may be stopped although, if desired, the thickness of metal before rolling may be predetermined by experiment or otherwise to produce the desired final thickness when the correct size of hole has been reached by rolling.

Fig. 2 shows a typical press for punching the holes in sheet metal before rolling. The press is constituted of two parts 17 and 18, the upper of which is given a reciprocating vertical motion by any suitable and well known mechanism and carries two or more rows of punches 19 made preferably of high speed steel such as tungsten drill rod. The movable part 17 comprises two plate members 20, 21 secured together by screws 22 so that when taken apart the punches may be inserted into countersunk holes provided in member 21 and securely held in proper position by the abutting upper plate member 20. The lower or stationary part 18 of the press may comprise two plate members 23, 24, which are held apart by spacers 25 to form a slot 26 through which the sheet metal is fed in any suitable manner. The part 18 contains a plurality of openings in alignment with the punches in the upper part and has its various sections secured together by screws 27.

Fig. 3 depicts the manner in which the sheet metal may be punched, two rows be-

ing cut or sheared at one operation, after which the sheet is moved downwardly, as shown, through the slot 26 a predetermined distance in order to punch the next pair of rows of holes. The sheet metal is of greater than the required thickness so that the holes may be quite large and the punches correspondingly more rugged and having less tendency to break during the shearing operation. It has been found that punches of .025 inches diameter and larger will readily and consistently penetrate sheet nichrome and other equally tough stock of thicknesses as great as .010 inches after which the metal may be rolled down to .005 inches thick or other desired dimension.

Fig. 4 represents a section of sheet metal so punched. When the sheet has been rolled in one direction in the manner shown in Fig. 9, the openings which originally were circular now become elliptical or elongated as indicated in Fig. 5, since the metal "cold flows" due to the pressure exercised by the rolls 27 and uniformly distorts the shape 25 of each opening. The final step is to feed the sheet metal through the rolls 27 in a direction transverse to the first direction, which operation tends to restore the original shape of each opening by causing further flow of the metal, and what is more important, to reduce the size of each opening.

These operations are carried out in such a manner that after the final roll the openings in the sheet metal are of the requisite size, also the shape of each hole conforms as closely as possible to that originally punched and the thickness of metal is substantially that required, although as pointed out hereinbefore, the matter of proper thickness 35 is the least important of the various requisites. These factors may be readily determined by experiment or calculation and are accurately reproducible in the same sheet metal.

45 It will be understood that if desired, the rolling operation may be stopped after passing the metal sheets through the rolls in one direction so as to obtain elongated openings, since apertures of any given shape may be 50 desirable to endow the tube with certain operating characteristics. The shape of the

openings may be minutely varied if desired, by rolling the sheet more in one direction than in another direction until the proper size and shape of opening is obtained.

The rolling process is also useful in obtaining shapes of apertures which would be prohibitive from a cost standpoint regardless of size of opening and regardless of the ease with which the metal may be worked. Thus, in Fig. 7 square apertures 70 have been punched with readily procurable square punches and upon rolling in one direction diamond-shaped openings appear, as indicated in Fig. 8 which could not have been punched economically due to the expense of fashioning diamond-shaped punches.

80 It will be evident from the foregoing that in addition to enabling the procurement of minute holes in relatively tough metal which is unattainable by prior art methods, my invention allows an enhancement of the accuracy of the shape, size and spacing of the holes because the latter are more easily and accurately punched when they are of substantial dimension prior to the rolling operation. Due to this increased degree of accuracy the holes as finally obtained are accurately reproducible.

85 What I claim as new and desire to secure by Letters Patent of the United States, is,—

1. The method of fabricating grid material which consists in perforating sheet metal with openings greater than the required size, then rolling the metal in two directions angular to one another in order to reduce the size of the openings and to obtain a predetermined shape of opening.

100 2. In the art of fabricating sheet metal grid material which is provided with openings of a shape different from the shape of standard perforating punches, the method which consists in perforating sheet metal of greater thickness than the final required thickness with openings readily procurable by punches of standard shape and then rolling the metal sheet a predetermined number of times in a plurality of directions until the final proper thickness of metal and the proper shape of opening are obtained.
